LOCKING ADJUSTMENT

Charles J. Stuart, Medford, Mass., assignor to
Wellman Company, Medford, Mass., a corpora-
tion of Maine

Application November 9, 1940, Serial No. 364,964

10 Claims. (Cl. 287—53)

This invention relates to a locking adjustment, more particularly a locking adjustment for blank cutting machines.

In sole cutting machines of the type shown in patents to McGowan No. 1,645,441, and Patten Nos. 1,270,319 and 1,418,604, the sheet stock to be cut is clamped between a pattern and a work table, and a knife is driven around the edge of the pattern to cut out the blank. This knife is driven by a series of flexible connections from an endless chain moving in an elongated path above the pattern. At an intermediate point in the driving connections they are constrained by a device termed a leader to follow a path more closely like the pattern than the elongated path of the drive chain. Also in order to provide for cutting soles larger or smaller than average both the chain drive and the leader are provided with adjusting mechanism to lengthen or shorten their effective paths, and these adjusting mechanisms are provided with rotatable hand wheels or knobs for actuating them.

The hand wheels, in the form shown in Figure 2 of Patten No. 1,418,604, are secured in an adjusted position by hand nuts or locking wheels threaded on the pins or shafts about which the hand adjusting wheels are rotated, and small friction washers have been placed between each hand nut and its adjusting wheel. These hand nuts therefore act to lock the adjusting hand wheels largely by the binding of their threads on the threads of the shaft, and due to the high speed of the machine and the irregular path in which the knife is moved the vibration is so great that considerable trouble has been found in retaining the adjusting hand wheels in locked position.

By the present invention an improved form of locking device for the hand wheels is provided, this device taking the form of a member having on opposite sides annular frictional bearing surfaces surrounding and radially spaced from the shaft or pin on which the hand wheel is mounted, and these opposed frictional bearing surfaces are engaged against corresponding surfaces on the adjacent sides of the locking hand wheel and the adjusting hand wheel or knob when the locking wheel is screwed up in the direction of the adjusting wheel.

An object of the present invention is to provide an improved locking mechanism for hand adjusting wheels or knobs.

Another object is to provide a locking mechanism having extended frictional bearing surfaces which give secure locking under conditions

of severe vibration without sacrifice of ready hand adjustment.

Other objects will appear from the detailed description and drawing, in which latter

5 Figure 1 is a longitudinal section through one form of the invention.

Figure 2 is a similar section of a modification, and

10 Figure 3 is a similar section of a further modification.

Referring to the specific embodiments shown in the drawing, in Figure 1 the numeral 1 is applied to a rotatable shaft driven from the main drive of a sole cutting machine such as 15 shown in the above named McGowan or Patten patents and this shaft carries a face plate 2 provided with a dovetail recess 3 in which is slidably mounted a block 4 carrying a crank pin 5. A pinion 6 is rotatably mounted on the crank pin 5 by means of a sleeve 7, and rigidly keyed on the sleeve 7 is an adjusting hand wheel 8. The pinion 6 engages a fixed rack 9 mounted on the face plate 2. Rotatably mounted on the sleeve 7 between the pinion 6 and hand wheel 8 is a 20 crank pin block 10, which is of the construction more fully shown at 55 in Figure 5 of the Patten Patent No. 1,270,319.

The outer end of the crank pin 5 is threaded and threadedly secured on this end is a nut 11 25 which is rigid or integral with a flexible disc 12, which latter adjacent its periphery is provided with an attached or integral frictional bearing ring 13 which may be of any suitable material such as soft metal, rubber, leather, or fibre. The nut 11 may be secured in adjusted position by the lock nut 14. Threaded on the end of the crank pin 5 outside of the lock nut 14 is the locking hand wheel or knob 15 which is provided with an 30 annular frictional bearing surface 16 of such a diameter as to locate it opposite the frictional bearing ring 13.

In the modification shown in Figure 2 the parts up to and including the hand adjusting wheel 8 are similar to those shown in Figure 1. Rigidly 35 secured on the crank pin 5, as by a set screw, is the hub 17 of a flexible disc 18, which disc at its outer periphery and on the side adjacent the hand wheel 8 is provided with an annular wedge shaped projection 19 which is adapted to cooperate in operation with a wedge shaped recess 20 on the face of the hand wheel 8 adjacent its periphery. A locking hand wheel 21 is threaded on the 40 end of the crank pin 5, and the disc 18 on the side opposite the annular projection 19 has a 45 wedge shaped annular projection 22 which in operation

eration is adapted to cooperate with a wedge shaped recess 23 on the inner face of the locking wheel 21. The projections 19 and 22 together form an enlarged ring adjacent the periphery of disc 18.

In the modification shown in Figure 3 the construction is, in general, similar to that shown in Figure 2, there being a hub 24 carrying a disc 25, which latter is provided on its face adjacent the adjusting hand wheel 8 with an annular wedge shaped projection 26 adapted to cooperate with a corresponding wedge shaped recess 27 in the hand wheel. On the opposite face of the disc 25 it is provided with a wedge shaped annular projection 29 for cooperation with a complementary wedge shaped recess 30 formed on the inner face of the locking wheel 28. The essential difference in this form from that shown in Figure 2 is that the hub 24, instead of being rigidly mounted on the crank pin 5, is slidably keyed thereon by the key 31, and therefore, in this form of the invention it is not essential that the disc 25 be made flexible.

In operation, in the form shown in Figure 1, the nut 11 carrying the flexible disc 12 and frictional bearing ring 13 is first threaded onto the crank pin 5 until the ring 13 nearly or lightly contacts with the face of the hand wheel 8, and the lock nut 14 is then screwed up against the nut 11, the binding of the nuts 11 and 14 against each other and on the threads of crank pin 5 holding the disc 12 firmly against rotary movement, after which the locking hand wheel 15 is threaded onto the crank pin 5. In adjusting during operation, the hand wheel 8 is turned until the desired position of the controlled machine part has been obtained, after which the locking hand wheel 15 is turned until it has forced the frictional bearing ring 13 into close frictional contact with the side face of the hand wheel 8. It will be seen that by the present invention the frictional bearing surface of the ring 13 is relatively large and spaced a considerable distance radially from the crank pin 5, and when the locking hand wheel 15 is screwed up its bearing surface 16 contacts with the disc 12 along an annular area directly behind the frictional bearing ring 13. The hand wheel 8 is thus secured in adjusted position by means of an extended frictional bearing which is practically independent of any jamming of threads on the crank pin 5, and in use the friction has been found to very effectively hold the parts in adjusted position notwithstanding severe vibration of the machine. A further advantage is that since the ring 13 is fixed against rotation there is no tendency by the locking wheel 15 when turned to alter the adjustment of wheel 8. Since the nuts 11 and 14 can be firmly locked by a wrench no difficulty is experienced securely holding the disc 12 against any tendency to rotate by reason of the frictional contact of the bearing surface 16 of the hand locking wheel 15.

In the form shown in Figure 2, when the locking wheel 21 is screwed up, the frictional bearing surfaces 19-20, and 22-23 are brought into engagement by reason of the flexibility of the disc 18 which permits a limited axial movement of the annular wedge shaped projections 19 and 22.

The operation of the form shown in Figure 3 is identical in all respects with that shown in Figure 2 except that, as before stated, the disc carrying the annular wedge shaped projections 26 and 29 is slidably mounted on the crank pin

so that the disc, its hub, and the wedge shaped projections are moved axially of the crank pin, thus obviating any necessity for making the disc 25 flexible.

5 It is obvious that the frictional engaging faces of the adjusting wheel, locking wheel and intermediate member can assume many varying forms without departing from the spirit of the invention.

10 While the invention has been shown and described as applied to sole cutting machines, of the type shown in the McGowan and Patten patents, it is also obvious that it is not limited to such use, and may be employed wherever 15 it is desired to fixedly secure an adjusting hand wheel against movement after adjustment.

Having thus described my invention, what I claim and desire to protect by Letters Patent is:

1. A locking adjustment comprising a support, 20 an adjusting member mounted on said support and rotatable in respect thereto, a manually rotatable locking member threadedly adjustable on said support toward and from said adjusting member, friction surfaces on the opposed faces 25 of said adjusting and locking members, a member non-rotatably mounted on said support and axially movable between said adjusting and locking members, friction surfaces carried by said non-rotatable member and operatively engageable 30 with said friction surfaces on said adjusting and locking members, and all of said friction surfaces having their outer peripheries spaced a substantial distance outwardly from the axis of rotation of said adjusting and locking members.

35 2. A locking adjustment comprising a shaft, an adjusting member rotatable on said shaft, a manually rotatable locking member threadedly adjustable on said shaft toward and from said adjusting member, friction surfaces on the opposed faces of said adjusting and locking members, a member non-rotatably mounted on said shaft and axially movable between said adjusting and locking members, friction surfaces carried by said last member and operatively engageable 40 with said friction surfaces on said adjusting and locking members, and all of said friction surfaces having substantially equal radii and their outer peripheries spaced outwardly from the axis of shaft close to the point of application of the 45 manual forces to said locking member.

50 3. A locking adjustment comprising a shaft, an adjusting member rotatably mounted on said shaft, a manually rotatable locking member threadedly adjustable on said shaft toward and from said adjusting member, said adjusting and locking members having opposed faces carrying annular frictional engaging surfaces, a ring-shaped member non-rotatably mounted on said shaft and axially movable between said adjusting and locking members, said ring-shaped member being provided with annular frictional engaging surfaces for contact with respective frictional engaging surfaces of said adjusting and locking members, and all of said friction surfaces being 55 concentric and having substantially equal maximum radii extending adjacent to the radius of application of the manual forces to said locking member.

4. A locking adjustment comprising a support, 60 an axially-stationary rotatable adjusting member, a locking member mounted on said support and threadedly adjustable toward and from said adjusting member, said members having opposed faces, a ring-shaped member non-rotatably mounted on said support but axially movable be-

tween said faces, and complementary frictionally engageable projections and recesses disposed on said faces and ring-shaped member.

5. A locking adjustment comprising a support, an axially-stationary rotatable adjusting member, a locking member mounted on said support and threadedly adjustable toward and from said adjusting member, said members having opposed faces, a third member non-rotatably mounted on said support but axially movable between said faces, and complementary arcuate projecting and recessed frictionally engageable areas disposed on said faces and third member.

6. A locking adjustment comprising a shaft, an adjusting wheel rotatable thereon, a locking wheel threadedly mounted on said shaft adjacent said first wheel, a ring non-rotatably mounted on said shaft and movable between said wheels, said ring having friction surfaces adjacent its periphery, and friction surfaces on said wheels cooperating with said first named friction surfaces.

7. A locking adjustment comprising a shaft, an adjusting member rotatable thereon, a locking member threadedly adjustable on said shaft toward and from said first member, said members having opposed faces, a relatively thin and flexible disc non-rotatably mounted on said shaft between said members, oppositely outwardly directed projections disposed adjacent the periphery of said disc, and recesses, complementary to said projections, disposed on the faces of said two members, walls of said projections and recesses forming frictionally engageable locking surfaces.

8. A locking adjustment comprising a shaft,

an adjusting member rotatable thereon, a locking member threadedly adjustable on said shaft toward and from said first member, said members having opposed faces, a disc non-rotatably mounted on said shaft between said faces and keyed to said shaft for axial movement thereon, and arcuate complementary projections and recesses on said disc and members, said projections adapted to be engaged in locking relation with said recesses by movement of said locking member.

9. A locking adjustment comprising a shaft, a hand wheel rotatable thereon in fixed axial position, a second hand wheel threadedly movable on said shaft toward and from said first wheel, a flat friction ring non-rotatably mounted on said shaft between opposed faces of said wheels concentrically of said shaft and movable only axially of said shaft, and adapted to frictionally engage the opposed faces of said wheels.

10. A locking adjustment comprising a shaft, a hand wheel rotatable thereon in fixed axial position, a second hand wheel threadedly movable on said shaft toward and from said first wheel, a flat friction ring concentrically and non-rotatably secured on said shaft between said wheels and resiliently movable axially of the shaft but fixed radially thereof, means for axially varying the location of said ring on the shaft, and said ring adapted to frictionally engage the opposed faces of said wheels upon movement of the second wheel toward the first.
